UNITED STATES PATENT OFFICE.

MICHAEL J. MANGAN, OF DES PLAINES, ILLINOIS.

CIGARETTE-PACKAGE HOLDER.

Application filed November 30, 1923. Serial No. 677,599.

It is generally known that those who are doing manual labor of various kinds, such as shop work, factory work, construction and building work, in carrying the popular brands of cigarettes which are done up in packages, in their pockets while performing their work, experience considerable difficulty in that the cigarettes become damp and moist, particularly where such work is being performed in warm climates or in a warm atmosphere, and in addition these packages being soft and pliable they become crushed, causing the cigarettes to crumble and burst. It is, therefore, an object of my invention to provide a light, rigid and inexpensive case for holding such packages against moisture or crumbling from the causes heretofore stated. With the cases which it has been attempted to use heretofore, under such conditions and by such classes of workmen, it appears that after the case has been carried for a while, particularly by those working in warm climates or warm atmospheres, there develops, due to sweating, a disagreeable odor. This objection or disadvantage I overcome by constructing my holder of aluminum.

It is a further object of my invention to provide a light, efficient and inexpensive holder, constructed of aluminum, with the parts so formed that the paper package is tightly, but yieldingly held in place under a spring-like pressure against accidental displacement of the package when the cover is removed.

It is a further object to provide a two part cigarette package case so designed that one part co-acts and grips the other at the various longitudinal corners thereof under a spring-like pressure, so that the parts will not become displaced one with respect to the other, and at the same time, is so constructed as to readily permit inserting one section or part within the other.

The above and other features of novelty, advantages and capabilities will become apparent from a detailed description of the accompanying drawings, in which I have illustrated a cigarette package holder embodying one form of my invention.

In the drawings, Fig. 1 is a perspective view of a cigarette package holder, embodying one form of my invention.

Fig. 2 is a sectional view of the holder, taken on the line 2—2 of Fig. 3.

Fig. 3 is a sectional view taken on the line 3—3 of Fig. 2.

Referring to the drawings in detail, both the body section 10, and the cover section, 11, are constructed of light, comparatively thin aluminum sheets, each being substantially rectangular in cross section. The side walls, 12, of the body 10, are concavo-convex, in other words, bowed inwardly intermediate its longitudinal edges, to afford a yielding spring in order to grip and hold the package of cigarettes therein under a spring-like pressure, so that the package may not drop out when the cover is removed. The side walls, 13, of the cover, 11, are also concavo-convex, so that the cover will grip the body, 10, at its longitudinal corners under a spring-like pressure, and yieldingly hold the parts together against accidental displacement. The two sections, 10 and 11, are, near their transverse edges, bulged outwardly, for example as shown at 14 and 15, to afford a ready gripping or grasping surface for the hands when pulling the two sections apart to permit access to the interior thereof. The ends, 16, of each section, that is, of the sections 10 and 11, are arranged at substantially right angles to the side walls and join such walls in substantially a right angle bend, so as to further accentuate the spring gripping action heretofore mentioned.

Having thus described my invention, what I claim is:

1. A cigarette holder comprising in combination a resilient body section open at one end only, and adapted to accommodate a package of cigarettes, the side walls being concave to yieldingly grip said package intermediate their vertical corners, and a resilient metal cover section adapted to fit over and to grip said body section near the vertical corners thereof, said cover having a bulged out portion having transverse edges to afford

a grasping surface when pulling said sections apart.

2. A cigarette holder comprising in combination a resilient body section open at one end only and adapted to accommodate a package of cigarettes, the side walls being concave to yieldingly grip said package intermediate their vertical corners, and a metal cover section adapted to fit over and to yield-

ingly grip said body section near the vertical corners thereof, said two sections having bulged out portions provided with transverse edges to afford a grasping surface when pulling said sections apart.

In witness whereof, I have hereunto subscribed my name to this specification.

MICHAEL J. MANGAN.
